INVENTOR

UNITED STATES PATENT OFFICE.

FREDERICK SNOW BOSWORTH, OF PROVIDENCE, RHODE ISLAND, ASSIGNOR
TO WEYBOSSET MILLS, OF SAME PLACE.

DESIGN FOR FANCY CASSIMERE.

Specification forming part of Design No. **8,007**, dated January 12, 1875; application filed January 2, 1875.
[Term of Patent 3½ years.]

To all whom it may concern:

Be it known that I, FREDERICK SNOW BOSWORTH, of the city and county of Providence, State of Rhode Island, have invented a new Design for Fancy Cassimere Fabrics; and I do hereby declare that the following specification, taken in connection with the drawings making a part of the same, is a full, clear, and exact description thereof.

The optical effect of my novel design will be apparent on an inspection of the accompanying drawings, to which reference is made. Said effect is produced by means of a plain woven ground, ornamented by stripes, which are of a peculiar composite character, and also by plain stripes, as hereafter more fully described.

Referring to the drawings, the stripes A are composed of a series of elongated crosses, *a*, in alternation with a series of transverse bars,

b. The stripes B are of so-called "crape-cord" weaving, running parallel with and placed equidistant from the aforesaid stripes A. The fabric may be made in any preferred variety or combination of colors for giving effect to the design above described, the characteristic feature of which is the crossed and barred stripes A in alternation and combination with the crape-cord stripes B upon a ground of plain weaving.

What I claim as my invention, and desire to secure by Letters Patent, is—

The design for fancy cassimere fabrics, as herein set forth, and represented in the drawings.

FREDERICK SNOW BOSWORTH.
